United States Patent Office

Des. 224,789
Patented Sept. 19, 1972

224,789

ELECTRIC CABLE

Bernard Edward Shlesinger, Jr., 9411 Macklin Court,
Alexandria, Va. 22309

Filed Feb. 3, 1971, Ser. No. 112,501

Term of patent 14 years

Int. Cl. D13—03

U.S. Cl. D26—1

Fig. 1

Fig. 2

FIG. 1 is a perspective view of an electric cable showing my new design; and

FIG. 2 is a perspective view of a modified form of the electric cable described in FIG. 1 showing my new design.

I claim:

The ornamental design for an electric cable, as shown and described.
